UNITED STATES PATENT OFFICE

WILLIAM D. BAYLEY, OF SPRINGFIELD, OHIO

FARROWING HOUSE

Application filed April 22, 1929. Serial No. 357,050.

This invention relates to farrowing houses for sows and their pigs, it more particularly relating to a structure which has separated hovering spaces for the pigs in communication with the pens, together with heating means for the hovering spaces.

An object of my invention is to provide a unitary structure containing separated hovering spaces and a heating means therefor to which unitary structure may be readily attached a plurality of hog houses in such a way that the hovering spaces will be in communication with the pens of the houses.

Other advantages and objects will appear from the following description and claims.

In the accompanying drawings:

Fig. 1 is a perspective view of a plurality of hog houses grouped about a common hovering and heating unit, illustrating the embodiment of my improvements both as to the construction of the unit and the arrangement of the houses therearound.

Fig. 2 is a plan view of a schematic nature illustrating the relation of the nursery pens with the several houses.

Fig. 3 is an enlarged partial transverse section on the line 3—3 of Fig. 2.

Fig. 4 is an enlarged partial longitudinal section on the line 4—4 of Fig. 2.

Fig. 5 is a horizontal section in reduced scale on the line 5—5 of Fig. 4.

Fig. 6 is an end elevation of a modification as to the type of house that may be employed with the hovering and heating unit as described.

Fig. 7 is a partial longitudinal section of the line 7—7 of Fig. 6.

Fig. 8 is a reduced scale elevation of a detail.

Referring to the drawings, and especially at this time to Fig. 2, a portable enclosure, indicated in general by the numeral 1, containing pig hovering spaces and a stove S, is placed on the ground, and a portable hog house placed at either open end thereof. The preferable construction of the hovering and stove enclosure is as herein shown, and the preferable grouping of houses about such an enclosure is also illustrated, it being understood that in the present case the preferred

construction only is shown, and that other constructions and methods of grouping within the scope of the claims, may be adopted as conditions warrant.

The hovering and heating enclosure proper is constructed as follows: A sheet metal floor piece 2 has secured to its side edges wall members 3 and 4, to which a roof member 5 is secured, one of the wall members being higher than the other so as to give to the roof a slope to provide a water shed for rain or snow. In the higher half of the roof 5 a superstructure 6 is attached having a sloping roof 6', the height of which is somewhat dependent on the type of stove S which is placed on the floor 2 under this roof 6'.

The stove S may be of any suitable kind, but is here shown as the well-known type brooder stove, and to permit access thereto for feeding purposes the roof 6 is provided with a fairly large aperture, over which a removable cover 7 is placed. The stove S has a flue 8 which passes upwardly through a thimble 9 secured in the roof member 6. Each open end of the structure thus formed is partially closed by a triangular strip 10 of sheet metal extending across the gables, its lower edge 11 being sufficiently high to allow the young pigs to pass thereunder.

The portable houses in which the sows are kept during the farrowing time are placed against the open ends of the hovering and heating enclosure 1. In Fig. 1 two houses are shown, these being indicated generally as 12 and 13. These houses may be the houses which the hog grower has on hand or may be new houses furnished with the hover and heating unit. In the latter event, the houses for reasons of economy in manufacture, are preferably alike, and, in the present instance each is divided into two pens by a partition formed of horizontal slats 14 and vertical battens 16, a fragment of one such partition being shown in the house 12.

Thus two houses so divided allow for the reception of four sows, and through an opening 17 in the end walls 18 of the houses 12 and 13, the young pigs may enter the hovering and heating enclosure 1 where their comfort in unseasonable weather is assured by

the deflected and radiated heat from the stove S. Access to the stove enclosure 1 through the openings 17 is permitted the young pigs at all times, regardless of the position of the sow, there being a horizontal rail 19 in each house, more clearly shown in the house 12 in Fig. 1. This rail 19 is spaced apart from the end wall 18 and is at a sufficient elevation above the floor 20 of the houses to permit the pigs to pass thereunder, but exclude the sow, and is secured in any suitable way to retain it in its position.

The floor space of the enclosure 1 is divided into a plurality of hovering spaces or pens by partitions. These partitions not only prevent contact of the young pigs with the heated stove itself, but also prevent intermingling of the various litters, although the latter object is essential only during the first few days after the pigs are farrowed.

A partition 21 is secured to the floor 2 and extends longitudinally through the stove enclosure 1, from one open end to the other, and forms a continuation of the house partitions referred to as the slats 14. A partition 22 is centrally located extending from the partition 21 to the wall 3 thus providing a pair of pens A and B (Fig. 5) to which the litters of the sows in the right hand end pens of the houses 12 and 13 may resort, while partitions 23 and 24, secured to the partition 21 and to the wall 4 provide pens C and D accessible to the left hand pens in the houses 12 and 13, and also provide between them a space E for the stove and accessibility thereto for the removal of ashes. The partitions 23 and 24 are preferably perforated to allow a greater proportion of radiated heat to escape to the pens C and D, while the slope of the roof 5 assures ample warmth in the pens A and B by downward deflection of the heated air currents.

The side walls 3 and 4 as well as the roof 5 and walls of the superstructure 6 are formed of sheet metal and are insulated by placing thereon sheets of insulating material such as asbestos paper as indicated at I in Figs. 4 and 5.

The rails 19 previously described form a hovering space in the houses which communicate with the hovering spaces A, B, C and D so as to provide ample space for the small pigs.

The preferable emplacement of houses and hovering and heating unit in the field is such that the side of the enclosure in which is the lower half of the roof 5 has a southerly exposure, there being a large aperture therein covered by a removable cover 25, which cover may be removed in bright weather to permit the young pigs to receive the beneficial effects of direct sunlight, and to accustom them to the colder outside air. This cover 25 preferably includes material suitable to admit the

ultra-violet rays of the sun as indicated at 25' in Fig. 1.

In Fig. 6, a modification is shown, it being an arrangement of a hovering and stove enclosure substantially as described previously, about which is grouped four separate houses 26 of a type known as A-houses. In this event the character of the sheet metal strips 10, Fig. 1, is altered to conform to that shown in detail in Fig. 8, in order to close the ends 75 of the stove enclosure between the pairs of houses. Openings 28 in the sheet 29 are provided and in alignment with these, apertures 30 are cut in the end walls adjacent the stove enclosure 1. In this Fig. 6 a modification is also shown in the form of the superstructure by which the height of the superstructure, indicated at 6^a is such as to accommodate the attendant to enable the attachment to enter the superstructure and have access to the stove for replenishing fuel, removing ashes and so forth. In this case the outer side wall of the superstructure will be provided with a door (not shown).

By this arrangement it will be seen that I have devised a simple, inexpensive means for supplying heated hovering spaces for and artificial heat to a plurality of farrowing houses, employing a minimum of new material, and permitting, to a great extent, the use of existing field houses. A further saving in material is effected by limiting the size of the stove enclosure to but little more than that needed for the stove itself, with ample hovering space thereabout to accommodate the several litters of very young pigs.

The structure as a whole is readily portable by reason of the fact that the central heating and pig hovering structure which is of a portable character may be readily separated from the houses, which are also of a portable character, so that the entire structure can be moved from place to place as occasion demands for sanitary reasons.

Having thus described my invention, I claim:

1. An enclosed unitary structure having a plurality of separated hovering spaces for pigs and a heating means therein, in connection with a plurality of separate hog houses all arranged about said unitary structure each in communication with one of the hovering spaces of said structure, the communication between each hog house and its associated hovering space being such as to exclude mature hogs from the hovering space.

2. A portable enclosed structure having a plurality of separated hovering spaces for pigs and a heating means therein with the hovering spaces arranged about said heating means, in connection with a plurality of portable separate hog houses all arranged about said unitary structure each in communication with one of the hovering spaces of said structure, the communication between each hog

house and its associated hovering space being such as to exclude mature hogs from the hovering space.

3. An enclosed structure having a stove 5 therein, a low-down substantially central partition extending entirely across said structure in one direction on one side of said stove, a single cross partition on one side of said central partition dividing that part of 10 the structure into two hovering spaces, and two other cross partitions on the opposite side of said central partition dividing that part of said structure into two hovering spaces and a stove space, in connection with 15 a plurality of separate hog houses arranged about said structure each in communication with one of said hovering spaces.

4. An enclosed structure having a stove 20 therein, a low-down substantially central partition extending entirely across said structure in one direction on one side of said stove, a single cross partition on one side of said central partition dividing that part of the structure into two hovering spaces, and 25 two other cross partitions on the opposite side of said central partition dividing that part of said structure into two hovering spaces and a stove space, in connection with a plurality of separate hog houses arranged 30 about said structure each in communication with one of said hovering spaces, said last mentioned cross partition being of a foraminous character.

5. An enclosed structure having side walls, 35 end walls and a roof, said end walls being open on their under edges, partitions in said structure dividing the same into a plurality of hovering spaces, heating means in said structure, and a plurality of separate hog 40 houses all arranged about said structure each in communication with one of the hovering spaces of said structure, the communication between each hog house and its associated hovering space being such as to exclude mature 45 hogs from the hovering space.

6. An enclosed unitary structure having a plurality of separated hovering spaces for pigs and a heating means therein, in connection with a plurality of separate hog houses 50 all arranged about said unitary structure with a pen in each of said houses, each of said houses having a hovering space in the end thereof communicating with its pen and also with one of the hovering spaces of said 55 unitary structure, the communication between the pen and hovering space of each house being such as to exclude mature hogs from the hovering space.

7. An enclosed unitary structure having a 60 plurality of separated hovering spaces for pigs and a heating means therein, in connection with a plurality of separate houses all arranged about said unitary structure with a pen in each of said houses, each of 65 said houses having a hovering space in the

end thereof communicating with its pen and also with one of the hovering spaces of said unitary structure, the hovering space in each house being formed by a low down horizontal rail extending transversely across the house. 70

8. An enclosed portable structure, the walls of said structure being provided with a plurality of openings at the floor level of a size to permit the passage therethrough of baby animals but exclude large animals, said 75 structure having a plurality of hovering spaces one for each opening with which the openings communicate, a plurality of houses for larger animals surrounding said structure, said openings furnishing communication between the hovering space of said structure and said houses.

9. An enclosed structure having a plurality of division walls separating the same into a heating compartment and a plurality of 80 nursery compartments, said division walls being arranged to permit said nursery compartments to be heated from said heating compartment, said heating compartment being accessible from one side of said structure, a removable cover arranged in the roof of said structure, said nursery compartments being arranged so that access may be secured thereto from each end of said structure, and a plurality of houses arranged at the ends of 85 the structure, with the houses in communication with corresponding nursery compartments, and means in said houses for excluding large animals from said nursery compartments. 90

10. A plurality of houses having pens for larger animals, a separate enclosed structure with which all of said houses are in communication, means for heating said enclosed structure, and a plurality of separated nursery compartments located partly in said enclosed structure and partly in said houses, and means in said houses for excluding the larger animals from said nursery compartments. 110

11. An enclosed portable structure consisting of a floor, sides and a roof, the floor being utilized as a nursery space for baby animals and divided into a plurality of nursery compartments, there being openings in the side walls of said structure leading from said compartments of a size to permit the passage therethrough of baby animals but exclude large animals, a removable cover for said roof, and a plurality of houses surrounding said structure, each house being in communication with a nursery compartment through the opening leading thereto. 115

In testimony whereof, I have hereunto set my hand this 20th day of April, 1929.

WILLIAM D. BAYLEY.
